United States Patent Office.

WILLIAM H. ELLIOT, OF NEW YORK, N. Y.

Letters Patent No. 65,802, dated June 18, 1867.

IMPROVED DRILLING MACHINE.

The Schedule referred to in these Letters Patent and making part of the same.

TO ALL WHOM IT MAY CONCERN:

Be it known that I, WILLIAM H. ELLIOT, of the city, county, and State of New York, have invented a new and improved Machine for Drilling Rocks, Ore, &c.; and I do hereby declare that the following is a full and exact description thereof, reference being had to the accompanying drawings, and to the letters of reference marked thereon. Similar letters of reference indicate the same devices in all the figures.

To enable others skilled in the arts to comprehend, make, and use my invention, I will proceed to describe its nature, construction, and operation.

The nature of my invention consists in connecting the crank of a rock-drilling machine to the drill-spindle, by means of a powerful spring, supported in its place by a suitable carriage, which slides upon or with the spindle; in the employment, in connection with suitable shoulders for a jar, of a spring which shall prevent the jar from taking effect, except when the drill sticks in the hole; in so employing the excess of motion in the drill-spindle over that indicated by the length of the cranks, that it shall cause the machine to feed toward the rock in proportion as the hole deepens, and in the employment of a peculiar pawl and rack for this purpose. It further consists in the use of a diagonal guide, which acts upon notches on the periphery of a collar or disk, which is attached to the drill-spindle, and in the employment of a windlass for raising and lowering the machine.

Figure 1 is a front elevation of my improved drill.

Figure 2 is a side elevation of the same.

Figure 3 is a section of the vertical feed devices.

Figure 4 shows two methods of applying the diagonal guide to the disk.

Figures 5 and 6 show another method of applying a diagonal guide to the disk.

a, frame of the machine which supports the fly-wheel, and all the other parts of the machine that move while it is in operation. Frame *a* slides vertically upon vertical bed-piece *b*. This gives to the machine the necessary feed motion. On the back of this bed-piece there is a circular projection, *c*, which is fitted to a circular bed-piece, *c'*, and is fastened to it by a central bolt. These serve as a joint, which allows the machine lateral motion, so as to point the drill to the right or left. The circular bed-piece *c'* is fastened to or cast upon the shaft *d*', which has its bearings in stands *d*. This allows the machine to take an inclination forward or back. The stands *d* are tightened upon the shaft *d*' by bolts *d*'''. The stands *d* are bolted to a platform, *p*, which, when used in deep cuts, is suspended by means of wire ropes or other adjustable supports, from or under a car, which runs upon ways on or above the surface of the earth. Arm *c*'' projects from the bed-piece *c'*, and supports a pivoted box, *e*', which serves as a bearing for screw *e*. Stand *g* is bolted to platform *p*, and supports on its upper end pivoted nut *e*''', through which screw *e* passes. This screw is turned by means of crank *f*, to bring the machine to, and hold it at any required inclination, either forward or backward. Fly-wheel *h* is connected, by means of cranks *h*' and connecting-rods *i*, with spindle-carriage *k*. This carriage has its bearings upon and moves vertically with the drill-spindle *l*. The drill-spindle has its bearings on the frame *a*, at *a*', through which it slides freely. Collar *m* is fastened permanently to the spindle *l*. Between the collar *m* and the end of the carriage, both above and below, there are strong spiral springs, *n* and *n*', shown in section, so that the spindle can slide through carriage *k* only to the extent allowed by the springs. *o*, windlass, *o*' crank, *o*'' rope for the purpose of raising the machine to clean the hole. *u*, feed-pawl, which holds the frame from sliding down on bed-piece *b*, until required to do so by the advance of the drill. The pawl *u* holds upon the rack *u*', which is attached to bed-piece *b*, and is composed of a series of pins passed through the bed-piece at equal distances one above the other. *m*', diagonal plate, the edge of which catches into notches on the periphery of collar *m*. This plate is hinged to carriage *k*, and is held against collar *m* by spring *m*''.

The operation of my improved rock-drill is as follows: When the machine is put in operation the carriage *k* receives a vertical motion, which is limited by the length of the crank, but the drill-spindle slides freely through the carriage *k*, being supported in its relation to the carriage only by springs *n* and *n*'. It has a motion considerably in excess of that given to the connecting-rods or indicated by the length of the crank. As the crank descends and passes the lower centre, the drill and drill-spindle, by their momentum, depress the spring *n* till the drill strikes the bottom of the hole. As the crank rises again and passes the upper centre, the upper spring *n*' is compressed, which adds its force to the motion of the crank, while descending, and shoots the drill

downward against the rock as an arrow is shot from a bow. As the hole deepens the spring n is more and more compressed at each revolution of the crank, till the collar m (see fig. 3) strikes the tail n'' of the feed-pawl u , when the point x is withdrawn from the rack u' , and the machine slides down on the bed-piece ζ , till the point x' comes in contact with the pin below it, which, owing to its shape, slides out of the rack, forcing point x into it again, so as to catch upon the next pin. In this way the machine is fed down as the hole deepens. The upper sides of points x and x' are so shaped that when the machine is drawn up by the windlass o , the pawl u passes easily over the pins of the rack u' , vibrating rapidly, like the escapement of a clock. By depressing pawl u by the finger, the machine may be let down after being raised, the pawl vibrating under the finger the same as when the machine was drawn up. As the drill-spindle slides up and down in carriage k , the collar m moves vertically under the diagonal edge of plate m' . This edge acts upon the notches on the periphery of the collar to revolve the drill-spindle. As the collar descends the edge of the plate has no tendency to turn it, as it takes no effect upon the notches; but when the collar rises a notch catches upon the edge of the plate, and follows it, giving to the drill a partial revolution at each upward motion of the crank. In case the drill sticks in the hole, as it often does, whether drilling by hand or by machinery, the spindle-carriage continuing its upward motion, depressing spring n , till the shoulder n'' strikes the collar m , and drives the drill and spindle upward with a heavy blow. A similar device, in some respects, is used in the machinery for drilling oil wells, called a jar, which jars each time the drill is raised; but this, by the employment of spring n , can only jar when the drill sticks in the hole, as the spring has sufficient strength, at other times, to raise the drill and spindle, thus avoiding the wear and tear of machinery consequent upon jarring at each upward motion of the drill. I employ the collar as a convenient opposing shoulder on the drill-spindle, for the purpose of jarring the drill upward. The upper end of the spindle might be enlarged, and the upper portion of the carriage allowed to strike it for the same purpose. Fig. 4 shows two diagonal plates operating upon the collar; one fastened to the carriage k , as shown in figs. 1 and 2, the other fastened to the frame a of the machine under the collar. The latter is a surer method than the former, as it acts upon the collar for the entire length of the motion of the spindle, while the former is operated only by the excess of the motion of the spindle over that of the carriage. Figs. 5 and 6 show another method of giving to the drill the necessary revolution. In this case the collar m has pins projecting from its periphery, which pass up and down in grooves s , v , and s' , in a plate fastened to the frame of the machine under the collar. One of the pins being in the upper end of the central groove v , in passing down raises spring t , and passes under it into the lower end of the groove. As it rises again the spring t guides it into the lateral groove s' , bringing the next pin into the groove s , from which it passes into the upper end of central groove v , and this operation is repeated at each revolution of the crank.

Having described my invention, what I claim, and desire to have secured to me by Letters Patent of the United States, is—

1. The carriage k , with springs n or n' , in combination with cranks h' and drill-spindle l , when operating substantially as herein shown and described.
2. Projections n'' , and a corresponding collar on the drill-spindle, in combination with spring n , when employed substantially as and for the purpose herein specified.
3. The combination of crank h' , drill-spindle l , and spring n , when employed as devices for producing excess of motion in the drill-spindle over that given to the connecting-rods by the cranks, which shall cause the machine to feed towards the rock, substantially as shown.
4. The pawl u and rack u' , when acted upon by devices producing excess of motion in the drill-spindle over that of the connecting-rods, for the purpose of feeding the machine towards the rock, substantially as herein set forth.
5. Plate m' , with its diagonal edge, when acting on the notches on the collar m , to revolve the drill, when operated upon by devices producing excess of motion in the drill-spindle over that of the connecting-rods, substantially as shown and described.
